(57) **CLAIM**

The ornamental design for a gift card, as shown and described.

DESCRIPTION

FIG. 1 is a front perspective view of a first embodiment of a gift card;

FIG. 2 is a front view thereof;

FIG. 3 is a left-side view thereof;

FIG. 4 is a right-side view thereof;

FIG. 5 is a top view thereof;

FIG. 6 is a bottom view thereof;

FIG. 7 is a back view thereof; and,

FIG. 8 is a back view of a second embodiment of the gift card of FIG. 1. The front, top, bottom, left, and right sides are identical to that which is shown in the first embodiment of the gift card.

The diagonal shading depicts portions of the gift card with a glossy surface.

All dashed broken lines and areas enclosed within dashed broken lines depict portions of the gift card that form no part of the claimed design.
